His Attorneys.

UNITED STATES PATENT OFFICE.

HEDLEY J. RICHARDS, OF ST. LOUIS, MISSOURI, ASSIGNOR TO LASALCO, INC., OF ST. LOUIS, MISSOURI, A CORPORATION OF MISSOURI.

ELECTROPLATING MACHINE.

Application filed May 26, 1924. Serial No. 715,356.

To all whom it may concern:

Be it known that I, HEDLEY J. RICHARDS, a citizen of the United States, residing at St. Louis, Missouri, have invented a new and useful Electroplating Machine, of which the following is a specification.

This invention relates to an electroplating machine, and has special reference to a machine in which the work being plated is continuously moved through the solution.

An object of the invention is to provide an improved electroplating machine of the motion type in which an inner group of anodes is continuously rotated in one direction, while the cathodes (the work being plated) are continuously rotated in the opposite direction between the moving anodes and an outer series of washer anodes.

Another object of the invention is to provide a machine of the character mentioned embodying novel means for supplying electrical energy to the anodes and the cathodes.

Another object of the invention is to provide a machine embodying novel means for imparting rotary movements in opposite directions to a series of anodes and to the cathodes.

Other objects will appear from the following description, reference being made to the drawings in which—

Fig. 1 is a plan view of my improved machine.

Fig. 2 is a side elevation of the operating mechanism, the tank and the carriers for the anodes and the cathodes being shown in section.

Fig. 3 is an enlarged sectional view of the mechanism for moving the cathodes and the inner series of anodes in opposite directions.

Fig. 4 is an enlarged view showing one of the brushes contacting with the cathode carrier forming a part of the electric circuit thereto.

Fig. 5 is a detail view of a part of the support for the brush forming a part of the circuit to the inner series of anodes.

The tank 1 containing the electrolytic solution has a non-metallic composition lining 2.

A pair of cross ties 3 are supported above the tank. An electric motor 4 mounted on a plate 5 of insulating material is supported near one end of the cross ties 3 and drives a shaft 6 having a worm thereon (Fig.

2) operatively engaging a worm gear wheel 55 7 attached to a shaft 8 rotative in a bearing 9. The shaft 8 has thereon a beveled pinion 10. The lower side of the pinion 10 meshes with a bevel gear 11 attached to a hollow shaft 12 rotative in bearings 13 supported by the cross ties 3. The gear wheel 11 which is attached to the shaft 12 operates upon an anti-friction thrust bearing 14 and thereby supports the shaft 12. The upper side of the pinion 10 diametrically opposite 60 from its engagement with the gear wheel 11 engages a beveled gear 14 attached to a shaft 15 through the medium of an insulation bushing 16 and a set screw 17. The shaft 15 extends axially through the hollow 65 shaft 12 and is insulated therefrom by an insulation element 18 and an insulation bushing 19 (Fig. 3). The element 18 is a combined washer and bushing, the washer portion thereof being upon an anti-friction 70 thrust bearing 20 resting upon the gear wheel 11. Thus the shafts 12 and 15 are simultaneously rotated in opposite directions by the pinion 10.

The hollow shaft 12 supports at its lower 80 end a cathode ring 21 from which the cathodes 22 (the work being plated) are suspended in the tank 1 and within the electrolytic solution therein.

The cathode ring 21 is insulated from the 85 shaft 12 by an insulation bushing 23 and is insulated from the supporting nut 24 by an insulation washer 25.

The anode ring 26 for the movable inner series of anodes 27 is attached to the lower 90 end of the shaft 15. The shaft 15 is capable of withdrawal from the shaft 12 when the anode ring 26 is detached, and to prevent contact of the ring 26 with the lower end of the shaft 12 an insulation washer 28 is 95 placed upon the anode ring 26. Thus it will be seen that the cathode ring 21 and the anode ring 26 are simultaneously rotated in opposite directions.

The outer series of anodes 29 are suspended from an anode ring 30 removably supported by brackets 31 attached to the upper end of the tank 1.

The circuit for supplying electrical energy to the inner movable series of cathodes 27 105 and to the outer stationary series of cathodes 29 includes a wire 32 connected with a metallic element 33 secured to insulation

supports 34 attached to the cross ties 3. A wire 35 leads from the element 33 to the outer stationary anode ring 30. An upright arm 36 in connection with the inner end of the element 33 pivotally supports an arm 37, the inner end of which has a clamp 38 engaging a brush 39 bearing upon the upper end of the shaft 15.

The connection between the arm 36 and the arm 37 comprises a pivot pin 40 extending through the arm 36 and supporting the arm 37, and a spring 41 encircling said pin. The spring 41 is held under compression because of its inner end bearing against the arm 36 and its outer end against an abutment 42 on the pin 40. A spring 43 connecting the stationary arm 36 with the pivoted arm 37 actuates the latter downwardly to press the brush 39 upon the upper end of the shaft 15. A wire 44 connects the arm 36 with the brush 39. Thus both cathode groups are energized by electrical energy delivered thereto through the wire 32.

25 A pair of brushes 45 on the lower ends of rods 46 operate upon a supporting part 47 in connection with the cathode ring 21. The rods 46 are supported in insulation bushings 48 in brackets 49. Below the brackets 49 each of the rods 46 is encircled by a pair of insulation sleeves 50 having flanges 51 on their lower and upper ends respectively. A coil spring 52 of the expansion type encircles the sleeves 50 and is held under compression by the flanges 51 thereby actuating the brushes into contact with the supporting part 47 of the cathode ring 21. A wire 53 leads from each of the rods 46 to a metallic element 54 mounted on the insulation supports 34 to which a circuit wire 55 is connected.

From the foregoing it will be seen that my invention, which is of a highly efficient and simplified nature, obtains all of its intended objects and purposes; may be readily assembled and taken apart, and may be manufactured at comparatively low cost. The fault of irregularities of anode and cathode surface, and varying and uneven current conditions are avoided. Irregular plating is eliminated, and the formation of gas infected areas around the cathodes is prevented. The positive inner anode group being moved through the solution in a direction opposite from the direction of movement of the negative cathode group supplies the needed metal very rapidly, and permits the use of much larger current density and amperage than is possible by different plating methods. In the case of nickel plating this machine prevents burning and produces a smooth, rapid and bright deposit. For brass plating rapid plating is possible, the motion being of great benefit in maintaining uniformity in

the color of this usually troublesome alloy solution. In the case of silver, copper and zinc plating it expedites the operation and gives a heavy smooth ductile deposit.

I am aware that the construction and relationship of parts may be varied without departure from the nature and principle of the invention. I do not restrict myself unessentially, but what I claim and desire to secure by Letters Patent is:—

1. An electroplating machine comprising a tank, means for supporting a series of anodes near the wall of the tank, a hollow shaft, a support for cathodes attached to said shaft, a shaft extending vertically through the hollow shaft and to a point below the lower end thereof within the tank, a support for anodes attached to said second shaft, and mechanism for rotating said shafts simultaneously in opposite directions. 80

2. An electroplating machine comprising a tank, means for supporting a series of anodes near the wall of the tank, a hollow shaft, a support for cathodes attached to said shaft, a shaft extending vertically through the hollow shaft and to a point below the lower end thereof within the tank, a support for anodes attached to said second shaft, mechanism for rotating said shafts simultaneously in opposite directions, and means for conducting electrical energy to said supports. 90

3. A machine of the character described comprising a rotary hollow shaft, a rotary shaft extending through the hollow shaft, a support attached to the lower end of each of said shafts, a gear wheel attached to each of said shafts, a pinion engaging each of said gear wheels and arranged to rotate said shafts simultaneously in opposite directions, a brush contacting with said second shaft, a device for actuating said brush into contact with said shaft, and means for conducting electrical energy to the support upon said hollow shaft. 100

4. A machine of the character described comprising a tank, an anode support within and near the wall of said tank, a hollow shaft, a cathode support attached to the lower end of said hollow shaft within the tank, brushes bearing against said cathode support, a shaft extending through the hollow shaft, an anode support attached to the lower end of said second shaft, a brush for contacting with said second shaft, a spring pressing said second brush into contact with said second shaft, and means for conducting electrical energy to said brushes. 115

5. A machine of the character described comprising a vertical tubular shaft, bearings in which said shaft is mounted for rotation, an anti-friction thrust bearing, a gear wheel attached to said shaft seated upon said anti-friction thrust bearing and supporting said shaft, an anti-friction bear- 125

- ing upon said gear wheel, a shaft extending through said tubular shaft, means insulating said second shaft from said tubular shaft, an insulation element upon said second shaft, an anti-friction bearing and supporting said gear wheel and thereby said second shaft, means engaging said gear wheels and operative to rotate them and said shaft simultaneously in opposite directions, an anode support removably attached to the lower end of said second shaft, and a cathode support removably attached to the lower end of said tubular shaft.
6. A machine of the character described comprising a vertical tubular shaft, bearings in which said shaft is mounted for rotation, an anti-friction thrust bearing, a gear wheel attached to said shaft seated upon said anti-friction thrust bearing and supporting said shaft, an anti-friction bearing upon said gear wheel, a shaft extending through said tubular shaft, means insulating said second shaft from said tubular shaft, an insulation element upon said second shaft, an anti-friction bearing and supporting said gear wheel and thereby said second shaft, means engaging said gear wheels and operative to rotate them and said shaft simultaneously in opposite directions, an anode support removably attached to the lower end of said second shaft, a cathode support removably attached to the lower end of said tubular shaft, an insulation device preventing contact of said anode support with said tubular shaft, and means for conducting electrical energy to said second shaft and to said cathode support.
7. A machine of the character described comprising a rotary shaft, a cathode support attached to the lower end of said shaft, an electrical contact brush bearing upon the upper end of said shaft, a spring actuating said brush into contact with said shaft, and electric circuit connections for conducting electrical energy to said brush.
8. A machine of the character described comprising a rotary cathode support, electric brushes seated upon said support, springs pressing said brushes upon said support, and wiring for conducting electrical energy through said brushes to said support.
9. A machine of the character described comprising a rotary shaft, a cathode support attached to said shaft, a rod, an electric brush in connection with said rod seated upon said cathode support, a spring encircling said rod and pressing said brush upon said support, and an electric wire connected with said rod.
10. A machine of the character described comprising a rotary shaft, a support in connection with said shaft, an electric brush contacting with said shaft, an arm holding said brush in contact with said shaft, a spring actuating said arm in a direction to contact with said shaft, and an electric wire leading to said brush.
11. A machine of the character described comprising a rotary shaft, a support in connection with said shaft, an electric brush contacting with said shaft, an arm holding said brush in contact with said shaft, a spring actuating said arm in a direction to contact with said shaft, an electric wire leading to said brush, a second shaft, a support in connection with said second shaft, and mechanism for rotating said two shafts simultaneously in opposite directions.
12. A machine of the character described comprising a tubular shaft, a support in connection with the lower end of said tubular shaft, an additional shaft extending through said tubular shaft, means insulating said two shafts from each other, a support attached to the lower end of said additional shaft, mechanism for rotating said two shafts simultaneously in opposite directions, and means for conducting electrical energy to said two supports.
